UNITED STATES PATENT OFFICE.

JOHN W. DE FORD, OF MARION, INDIANA.

STREET OR STATION INDICATOR.

1,083,063.

Specification of Letters Patent. Patented Dec. 30, 1913.

Application filed January 18, 1913. Serial No. 742,852.

To all whom it may concern:

Be it known that I, JOHN W. DE FORD, a citizen of the United States of America, residing at Marion, in the county of Grant 5 and State of Indiana, have invented certain new and useful Improvements in Street or Station Indicators, of which the following is a specification.

This invention relates to certain new and 10 useful improvements in street or station indicators; the object being to provide a device by means of which the streets on the route of a car can be indicated in succession as they occur, thereby announcing to the 15 passengers of the car, the name of the street at which the car will next stop.

A further object of the invention is to 20 provide an indicator which can be operated either by hand or foot by the motorman or conductor, in order to cause the name of the next street to appear in clear view of the 25 passengers, thereby overcoming the disadvantages now existing in carrying passengers by their stops or streets.

25 A further object of the invention is to provide a device in which an apron is used on which are printed consecutively, the names of the streets or stations as they occur, said apron being carried by rolls capable of being 30 operated independently so that after the car has reached its terminal by shifting the operating mechanism, the apron can be rewound upon the roll in order to bring the names of the streets into the view of the 35 passengers, on the return trip of the car.

A further object of the invention is to 40 provide a station indicator in which a centrally driven gear is employed which can be driven by any suitable means; said gear co-acting with pinions carried by the web rolls alternatively, in order to cause either of said rolls to be rotated so as to wind the apron thereon containing the inscriptions.

45 A still further object of the invention is to provide a station indicator which is so constructed that the apron-carrying roll will be rotated a certain distance upon each operation in order to cause the apron to move the required distance to bring the next 50 station or street printed upon the apron into a line with the sight opening.

55 Other and further objects and advantages of the invention will be hereinafter set forth and the novel features thereof defined by the appended claims.

In the drawings—Figure 1, is a front ele-

vation of my improved station indicator; part of the casing being broken away to show the driving mechanism; Fig. 2, is an end view of the same; the end plate being 60 removed to show the driving mechanism in elevation, said view also illustrating the operating mechanism which can be installed at any desired point; Fig. 3, is an elevation of the spring lock for preventing the driving gear from rotating in a reverse direction for holding the same in the position in which it is moved; Fig. 4, is an elevation of the operating lever; Fig. 5, is a face view of the same; Fig. 6, is a front view of one of 70 the clips for locking the pinion in its desired position; and Fig. 7, is a side view of the same.

Like numerals of reference refer to like parts in the several figures of the drawings. 75

In the drawings, 1 indicates a rectangular casing formed of any suitable metal having a partition 2 forming a roll compartment 3 and a mechanism compartment 4. The roll compartment 3 is closed by a hinged door 5 80 having a sight opening 6 over which is preferably arranged a plate of glass. The mechanism compartment 4 is inclosed by a suitable plate, not shown.

Mounted in suitable bearings formed in 85 the end of the casing and the partition 2, are shafts 7 and 8 upon which are secured rolls 9 and 10 having longitudinal notches formed in their periphery in which is secured the ends of an apron 11 by clamping 90 means 12, as clearly shown, which may comprise screws or a plate and said apron is provided with inscriptions printed thereon, herein shown the names of streets on the route of the car to which the station indicator is to be attached. The apron 11 passes over guide rollers 13 and 14 arranged longitudinally within the casing adjacent the front door thereof in order to hold the apron tightly stretched in front of the sight opening to enable the name of the street or station to be clearly read by the passengers of the car as said name appears in front of the sight opening. 95

The ends of the shafts 7 and 8 extend into 105 the mechanism compartment 4 and have feathered thereon, pinions 15 and 16 which are provided with integral sleeve portions 17 and 18 terminating in shaft portions 19 and 20 which extend through suitable openings formed in the end of the casing of the compartment 4 and are preferably provided

with knobs 19' and 20' in order to allow the same to be readily grasped in order to move the pinions upon the respective shafts for the purpose hereinafter fully set forth. The 5 shafts 19 and 20 are provided with collars 19² and 20² which limit the inward movement of the shafts and said shafts are also provided with annular grooves 19³ and 20³ which are adapted to be engaged by sliding 10 clips 21 mounted upon the end of the casing; said clips being provided with bifurcated lower ends adapted to fit within the grooves so as to lock the shaft in extended position and to straddle the shafts to 15 the outside of the collars 19² and 20² to lock the shafts when forced inwardly. By this construction, each shaft can be locked in the desired position without any danger of it moving and by forming the clips with lips 20 as clearly shown, they can be readily manipulated by the conductor or motorman. The preferred form of mounting these clips is to provide the same with a longitudinal slot through which extends a screw for securing the clips to the casing in order to 25 allow the same to slide up and down and out of engagement with the shafts.

Extending inwardly from the partition 2 is a bearing 22 in which is mounted a shaft 30 23 having a crank receiving portion 24 at its outer end arranged in such a position that a crank can be readily placed thereon in order to rotate said shaft. Mounted on the shaft 23 is a driven gear 25 having a 35 washer arranged to each side and said driven gear is provided with a ratchet face, as shown at 26 formed by providing the face with a series of tapering recesses terminating in vertical walls as shown at 27. On 40 the shaft 23 to the outside of the driven gear 25 is mounted the collar portion 28 of a spring-operating lever 29, which is held in position thereon by a nut 30 and said lever is provided with an offset portion 31 having 45 projecting therefrom, a beveled lug 32 corresponding in shape to the recesses formed in the face of the driven gear 25 and adapted to be normally held into one of these recesses by the resiliency of the lever. From 50 the above, it will be seen that by oscillating the lever 29, the driven gear will be rotated, or that by placing a crank on the end of the shaft 23, the gear can be rotated in order to rotate one of the pinions 15 or 16, 55 as the case may be.

In order to provide means for driving the driven gear by the operating lever in such a manner that the conductor can operate the same either by hand or a treadle, I provide 60 the lever 29 with an operating rod 33 which extends through a slot 34 formed in the casing and is provided with suitable stops 35 for limiting the movement thereof. The rod is provided with a turn buckle for adjusting 65 the length of the same in order to obtain

the correct throw of the lever so as to rotate the driven gear the desired distance which in turn will rotate the pinion in mesh therewith sufficiently to bring the name of one of the streets upon the apron in line with the sight opening. Herein shown, I provide a crank 37 to which the end of the rod 35 is connected; said crank being preferably mounted upon a bracket 38 secured to the car at the desired point and to the other arm of the crank 37, I connect a rod 39 which extends down to a point adjacent the floor and is connected to a pivoted treadle 40 mounted in a bracket 41 and while I have shown a treadle for operating the driven gear it is of course understood that by providing the rod 39 with a handle or grip of any kind, the same can be readily grasped and drawn downwardly by the conductor or motorman to operate the pivoted lever. In 70 order to return the pivoted lever 29 to its starting position, I provide a coil spring 42 one end of which is connected to the lever and the other end to a suitable bracket 43 extending from the casing. 80

In order to prevent the driven gear from being rotated in a reverse direction by the spring lever when returned to its normal position by the spring 42, I provide a spring catch 44 which is provided with an angle end 45 carrying a projection 46 adapted to co-act with one of the recesses of the ratchet face of the driven gear and prevent the same from turning in one direction. For preventing the idle pinion from turning 90 backwardly so as to loosen the web, I provide the partition 2 with suitable housings in which are mounted spring-actuated bolts 47 which pass through plates 48 inclosing the housings and are provided with beveled 95 ends adapted to co-act with the teeth of the idle pinion, as clearly shown in Figs. 1 and 2, whereby the idle pinion is allowed to rotate in one direction, but is prevented from rotating in a reverse direction. 100

From the above, it will be seen that I have provided a station or street indicator in which a pair of roll-carrying shafts are employed having driven pinions feathered thereon and capable of being manually 115 thrown into and out of mesh with a central driven gear in order to rotate either of said roll-carrying shafts in such a manner that the apron carried thereby will be moved a certain distance and held in that position 120 until the device is operated manually again by the motorman or conductor; the movement of said apron being sufficient to shift the position of the apron within the housing so as to bring the streets or stations printed 125 thereon in order, into the view of the passengers on the car; whereby it will not be necessary for the conductor to announce the names of the streets or the stations as the car approaches the same, as the passengers 130

will have clearly before them, the names of the streets or stations; thereby enabling the conductor or motorman to attend strictly to his other duties.

5 While I have shown the rod 39 constructed in such a manner as to be operated manually, it is of course understood that suitable operating mechanism can be employed, such as electrical means, without departing from 10 the spirit of my invention.

The operation of a station indicator constructed as hereinbefore set forth, is as follows: Supposing that the gears are in the position as shown in Figs. 1 and 2, by operating the treadle 40 so as to rock the lever 29 the driven gear will be moved a distance equal to the distance between the stops 35 of the rod 33 which in turn will drive the pinion 15 carried by the shaft 7 and the roll 20 will be rotated so as to cause the apron to be wound thereon, and as shown in Fig. 1, the name of the street "Washington," will be carried from in front of the sight opening and the next street will be brought 25 into alinement with the sight opening. When the treadle is released, the spring 42 returns the lever 29 to the position shown in Fig. 2, the catch 44 preventing the driven gear from being turned backwardly, and it will be seen that on each 30 operation of the treadle or a downward movement of the rod 39, the driven gear will be rotated. After the car to which the indicator is attached has reached the end of the 35 line or the terminal, the motorman operates the upper sliding clip 21 so as to disengage the same from the shaft 19 and by forcing the same inwardly, the pinion 15 is thrown out of engagement with the driven gear 25, 40 at the same time it is thrown into engagement with the spring catch 47 so as to prevent any unwinding of the roll thereon. The sliding clip 21 is then moved upwardly and the shaft 20 is drawn outwardly until 45 the groove is brought into alinement with the clip and the same is forced downwardly so as to lock the pinion 16 into engagement with the driven gear 25. As the driven gear is operated when the parts are in this position, 50 the lower roll or empty roll will be rotated so as to wind the apron thereon and bring the names of the streets thereon, intermittently into the view of the passengers of the car.

55 It will be seen that I have provided means whereby the driven gear can be operated directly from the shaft upon which it is mounted, or operating means as herein shown and described, can be employed which 60 can be located at any desired point upon the car at a convenient place for the conductor or motorman.

I claim:

1. In a street or station indicator, the combination with a pair of shafts carrying rolls,

an apron mounted upon said rolls, pinions feathered upon said shafts, a driven gear, means for locking said pinions into and out of mesh with said driven gear, means for holding said driven gear against backward movement thereof, spring-actuated members adapted to be engaged by said pinions when in inoperative position for holding said pinions against backward movement thereof, and a pivoted spring lever for operating said gear. 70

2. In a street or station indicator, the combination with a pair of apron-feeding shafts, of pinions feathered upon said shafts, a driven gear, means for moving said pinions into and out of mesh with said gear, means for locking said pinions in adjusted position, spring-actuated bolts co-operating with said pinions alternately, and means for driving said driven gear. 80

3. In a street or station indicator, the combination with a casing provided with compartments, of rolls mounted in one of said compartments, driving mechanism mounted in the other compartment comprising pinions and a gear, means for connecting said driving mechanism to either of said pinions, and means coacting with said idle pinion for preventing backward movement thereof. 90

4. In a street or station indicator, the combination with a casing, of shafts mounted in said casing, rolls carried by said shafts, an apron carried by said rolls, pinions feathered on said shafts provided with shaft portions extending through one wall of said casing, a driven gear, means for locking said shafts in adjusted position, and spring members co-acting with said pinions for preventing movement in one direction. 100

5. In a street or station indicator, the combination with a casing, of roll-carrying shafts mounted in said casing, pinions feathered on said shafts, a driven gear, means for moving said pinions into and out of engagement with said driven gear, and spring-actuated bolts having beveled ends co-acting with the idle pinion for preventing backward movement thereof. 110

6. In a street or station indicator, the combination with a pair of roll-carrying shafts, of pinions on said shafts, spring-actuated bolts adapted to be engaged by said pinions, a gear provided with a ratchet face for driving said pinions, a pivoted spring lever provided with projections co-acting with the ratchet face of said driven gear, means for oscillating said lever in one direction, a spring for returning said lever to its original position, and means for preventing backward movement of said driven gear. 115

7. In a street or station indicator, the combination with a pair of roll-carrying shafts, of pinions upon said shafts, spring-actuated bolts adapted to be engaged by said pinions, 130

a driven gear provided with a ratchet face, a spring lever provided with projections co-acting with the ratchet face of said gear, an operating rod connected to said lever, and a spring catch co-acting with the ratchet face for preventing rearward movement thereof.

8. In a street or station indicator, the combination with a pair of shafts, of rolls carried by said shafts, an apron carried by said rolls, pinions feathered upon said shafts provided with shaft portions extending through the wall of said casing, spring-actuated bolts adapted to be engaged by said pinions, a driven gear for driving said pinions, and sliding clips for locking the pinion-carrying shafts in adjusted position.

9. In a street or station indicator, the combination with a driven gear, of apron-carrying rolls, shafts for driving said rolls, pinions for driving said shafts, sleeves for shifting said pinions into and out of engagement with said driven gear, and slidably mounted members for locking said driven gear against movement in one direction.

10. A station or street indicator comprising a pair of shafts carrying rolls, pinions feathered on said shafts, a driven gear,

means for moving said pinions into and out of mesh with said driven gear, spring-actuated bolts co-acting with said pinions, means for locking said pinions in their adjusted positions, and means for preventing said driven gear from rotating in one direction.

11. In a street or station indicator, the combination with a casing provided with a hinged door having a sight opening, of shafts carrying rolls mounted in said casing, an apron mounted upon said rolls passing over said sight opening, pinions carried by said shafts, spring-actuated bolts co-acting with said pinions, a gear for driving said pinions provided with a ratchet face, a spring lever provided with projections co-acting with the ratchet face of said gear, a spring catch provided with a projection co-acting with the ratchet face of said gear for preventing reverse movement thereof, a rod connected to said lever, and means for reciprocating said rod.

In testimony whereof I affix my signature in presence of two witnesses.

JOHN W. DE FORD.
